UNITED STATES PATENT OFFICE.

PHILIP L. SERWE, OF CHICAGO, ILLINOIS, AND GEORGE C. DICKEY, OF SEATTLE,
WASHINGTON.

REFRIGERATOR DISPLAY VENDING-VEHICLE.

1,340,853.

Specification of Letters Patent. Patented May 18, 1920.

Application filed March 25, 1919. Serial No. 285,121.

To all whom it may concern:

Be it known that we, PHILIP L. SERWE and GEORGE C. DICKEY, citizens of the United States, residing at Chicago, in the 5 county of Cook and State of Illinois, and at Seattle, in the county of King and State of Washington, respectively, have invented a certain new and useful Improvement in Refrigerator Display Vending-Vehicles, of 10 which the following is a full, clear, concise, and exact description, reference being had to the accompanying drawings, forming a part of this specification.

Our invention relates to refrigerator display vending vehicles and has to do more particularly with a vehicle of this character for handling meats in which an inclosed body is provided having a transparent display case located within the body and suitably connected with refrigerating means 15 preferably in the form of one or more ice chests located alongside the display case. This outfit is suitably built into the body portion and located so as to provide an attendant's floor space alongside the show case, this space being connected with a space in front where a driver's seat is provided, the body being preferably placed upon the chassis of an automobile. The display case 20 is preferably arranged along the curb side of the body, that is, the right side, which is the curb side as it is generally called. A suitable door is provided for closing the display side and which may be opened when 25 the vehicle is drawn up to the curb, so as to expose the case and contents to view. Thus a very neat and attractive portable conveyance is provided for the display of meats, etc.

40 Referring now to the accompanying drawings for a more detailed disclosure of our invention,

Figure 1 is a side elevation of our improved vehicle with the side door open displaying the display case and a portion of the side wall broken away to show one of the ice chests;

Fig. 2 is a section just above the display case showing a floor plan of the vehicle;

50 Fig. 3 is a transverse section along the line 3-3 of Fig. 1, and

Fig. 4 is a section along the line 4-4 of Fig. 1 showing the transparent display case and connected rear ice chest.

55 Referring now more in detail to the pre-

ferred form of our invention as illustrated, it comprises an inclosed body portion placed upon a suitable chassis 5 as of an automobile. The body is preferably made as wide as possible and therefore the floor 6 is extended 60 so as to project over the wheels, being cut away at the rear wheels 7 and provided with suitable mud guards 8. Along the curb side of the body we provide a suitable display case 16 preferably having a glass front and 65 top with sliding rear doors and connected with refrigerating apparatus in the form of a front ice chest 9 and rear ice chest 10 so as to provide a circulation of cold air through the display case. This, of course, keeps the 70 interior of the case cooled so as to preserve the meats and other articles kept therein. These chests have removable covers for refilling and cleaning.

In order to protect the display case when 75 necessary, we provide a movable door 15 preferably hinged at 11 and controlled from the interior of the body by the attendant. For this purpose we provide a suitable lever 12 connected with the door 15 and acting 80 upon a ratchet 13 so that the door may be held in its open position. Thus the attendant may open and close the door from the inside.

A floor space 14 for the attendant is provided alongside the display case 16 so that ready access may be had to the case and also to the ice chests without having to leave the vehicle. Also, at the front end of the vehicle a space 17 is provided for the driver 90 at which a seat 18 is placed adjacent the steering wheel 19 and a suitable door is placed along the curb side for entering and leaving the vehicle.

Thus the attendant may drive the vehicle 95 from place to place, control the opening and closing of the door 15 and wait upon the customers without having to leave the interior of the machine. When getting ready to display his wares, he simply drives up to 100 the curb or any place where it is desired to stop, and opens the side door 15 by means of the lever 12 so as to expose the display case 16 and contents to view to the prospective customers.

105 A neat, clean, sanitary and attractive portable shop is thus provided, in which perishable goods may be kept in a cooled state due to the circulation of cold air through the case from the connected ice 110

chests. Also ready access may be had to the display case and customers easily waited on without the attendant having to leave the machine. The machine is driven up to the curb and opened and the customers can step to the side of the machine and select cuts of meat just as is done in the ordinary butcher shop.

Although we have shown a preferred design it is to be understood that we contemplate other arrangements than the particular one shown. For instance, the display case may be varied or any number of ice chests provided. Also the side door need not be controlled by any particular kind of lever.

Therefore we do not desire to be limited to the exact structure shown and described but aim to cover all that which comes within the spirit and scope of the appended claims.

We claim—

1. In a display vending vehicle, a body comprising a display case along the curb side, an attendant's space along the case, and suitable refrigerating means for the display case, said means comprising an ice-chest at the forward end of the display case and an ice-chest in the attendant's space adjacent the rear end of the display case.
2. In a display vending vehicle, a body comprising a display case along the curb side and having a transparent side and a transparent top, an attendant's space along the case, said case and space being confined by suitable walls, a movable door extending at one side of and above the case adapted to be opened to expose the side and top of the display case to view along the curb side, and suitable refrigerating means for the display case.
3. In a display vending vehicle, a body comprising a display case with transparent side and top along the curb side, an attendant's space along the case, said case and space being confined by suitable walls, a movable door extending at one side of and above the case adapted to be opened to expose the side and top of the display case to view along the curb side, and suitable refrigerating means for the display case, means controlled by the attendant from inside the body for opening and closing the door.
4. A body for display vending vehicles comprising a walled inclosure adapted to fit the chassis of an automobile and extending over the rear wheels thereof, a display case along one side of the body over the rear wheel position along the curb side, an at-

tendant's space along the other side over the other wheel position, and refrigerating means for the display case comprising an ice-chest at the forward end of the display case and an ice-chest in the attendant's space adjacent the rear end of the display case.

5. A body for display vending vehicles comprising a walled inclosure adapted to fit the chassis of an automobile and extending over the rear wheels thereof, a display case along one side of the body over the rear wheel position along the curb side, an attendant's space along the other side over the other wheel position, and suitable refrigerating means carried within the body for the display case, said means comprising an ice-chest at the forward end of the display case and an ice-chest in the attendant's space adjacent the rear end of the display case.

6. A body for display vending vehicles comprising a walled inclosure adapted to fit the chassis of an automobile and extending over the rear wheels thereof, a display case with transparent side and top along one side of the body over the rear wheel position along the curb side, a movable door closing one side of the vehicle and adapted when open to expose the display case and provide an opening above the case to the attendant's space, an attendant's space along the other side over the other wheel position, and a suitable driving seat at the front end communicating with the attendant's space, said movable door being pivoted along its upper edge so that it may swing outwardly to provide a shelter for the exposed display case.

7. A display vending vehicle for meats comprising a suitably walled body adapted to fit a running gear of a vehicle, an attendant's space within said body, a transparent display case within the body along the curb-side, a movable door closing one side of the vehicle and adapted when open to expose the display case and provide an opening above the case to the attendant's space, and an ice chest positioned alongside the display case and connected therewith so as to supply a cold air circulation to the display case.

In witness whereof I hereunto subscribe my name this 7th day of February, A. D. 1919.

PHILIP L. SERWE.

In witness whereof I hereunto subscribe my name this 24th day of Feb'y, A. D., 1919.
GEORGE C. DICKEY.
